(Cl. 2—114)

This invention relates to a bed cover and more particularly to a combination bed cover and garment for babies and children wherein the child may be securely and safely held in bed and beneath the covers on the bed.

An object of the invention is to provide a bed cover which may be easily maintained in position over a child in the bed. Another object is to provide means for safely and securely holding children in bed. Still another object is to provide a bed cover wherein the lower portion of the body of a child is secured to the central portion of the cover and the child is held in position with respect to the cover.

Another object of the invention is to provide a bed cover which securely holds a child in position in bed and which, at the same time, provides room for movement of the child beneath the covers on the bed. Yet another object is to provide a combination garment and bed cover wherein the cover is secured to the garment and is fixed in position on the bed.

Other features and advantages will appear from the following specification and drawings, in which—

Figure 1 is a plan view of the cover in the position in which it is adapted to be secured to the bed; Fig. 2 is a plan view of the garment for the child with the cover turned back and partly broken away; Fig. 3 is a plan view of the upper section of the cover detached from the other sections; Figs. 4 and 5 are plan views of the side sections of the cover detached from the other sections; Fig. 6 is a plan view of the lower section of the cover detached from the other sections; Fig. 7 is a plan view of the front portion of the garment; Fig. 8 is a plan view of the rear portion of the garment; Figs. 9, 10, 11 and 12 are plan views of the rear, front and two sleeve sections respectively, of a modified form of garment; Fig. 13 is a plan view of the modified form of garment in assembled relation.

In all of the drawings the views are taken from above since both the cover and the garment are normally disposed in horizontal position.

In the embodiment of the invention described herein and referring particularly to Figs 1 and 2, a rectangular cover 10 of any suitable fabric is formed from the sections 11, 12, 13 and 14, the sections being secured to each other along the seams 15, 16, 17 and 18. Each of the sections is provided along its outer edges with a seam forming the hem 19. If desired, a suitable bind-

ing tape may be secured to the outer edges of the cover instead of forming the hem 19.

A rectangular flap 20 may be secured to the cover along the upper edge thereof, as shown in Fig. 1, or, if desired, the flap 20 may be made integral with the section 14. Any suitable means may be provided for opening the section 14 and the flap 20 secured thereto along the central longitudinal line of the section. Preferably, as shown, the means may consist of a "hookless" slide fastener 21.

To the corners of the cover 10 may be secured suitable tie members 22 and 23. Preferably the corner portions of the cover are equipped with loops 24 through which the tie members 23 may be passed. However, if desired, the tie members, as shown at 22, may be integrally formed with the cover.

Referring particularly to Fig. 2, a garment 25 of any desired type may be secured to the cover 10. The garment may include a central body portion 26 and leg portions 27. Shoulder portions 28 provide armholes 29. A "hookless" slide fastener 30 extending longitudinally along the central portion of the garment may be used to open and close the same.

The garment 25 is secured to the cover 10 along the lower portion of the garment. Preferably the garment is attached to the cover along the reinforced seam 32 with the seam 32 extending across the crotch of the garment and along a portion of each of the leg openings 33. "Hookless" slide fasteners 34 may be provided along the seam 32 between the cover and the garment. If desired, the garment may be attached to the cover as seen in Fig. 1 by merely securing the crotch portion of the garment to the cover by sewing the parts together.

A tuck 31 in the lower portion of the garment permits adjustment of the length of the garment when desired.

As seen particularly in Figs. 3, 4, 5 and 6, the cover consists of the sections 11, 12, 13 and 14 which are secured to each other along their edges in the relation shown in the drawings. The section 12 is preferably provided with two arcuate surfaces 35 and 36 while the section 14 is equipped with similar arcuate edges 37 and 38. When the sections 11, 12, 13 and 14 are secured to each other along the seams 15, 16, 17 and 18, the arcuate edges 35 and 37 are straightened and form the upper and lower edges of the cover. The arcuate edges 36 and 38 are partially straightened as are the edges of the sections 11 and 13. The distortion of the normal shape of

the sections which occurs when securing them to each other to form a cover of the rectangular shape shown in Fig. 1 produces infolds 39 in the surface of the cover particularly on both sides of the central longitudinal line thereof. As a result of these infolds, elongated longitudinal pockets or recesses are formed on both sides of the longitudinal central line of the assembled cover.

Referring particularly to Figs. 7 and 8, the garment 25 may be formed of a front section 40 and a rear section 41 which are secured to each other along the peripheral edges thereof to form the garment shown in Fig. 2.

A modified form of garment shown particularly in Figs. 9 to 13 may, if desired, be used in combination with the cover. This garment is formed of the front section 42, the rear section 43 and the sleeve sections 44 and 45. The edges 46 of the sleeve sections are secured to adjacent portions of the front and rear sections to provide the sleeves 47 in the garment shown in Fig. 13. Each of the sleeves may also be secured to the opposed portions of the same sleeve along the entire peripheral edge to form a sleeve which is closed at the end. The front and rear sections of the garment are secured to each other in the same manner as are the front and rear sections of the garment 25. The garment 49 may be secured to the cover in the same manner as that described and shown in connection with the garment 25. The tuck 48 in the lower portion of the garment 49 corresponds to the tuck 31 in the garment 25 and is used for lengthening the garment when adjustment is desired.

Any suitable material or fabric may be used for the cover and for the garment. Preferably, the cover is formed of a fabric such as celanese or muslin and the garment may be formed of a fabric such as cotton or rayon.

By referring herein to a garment to be secured to the sheet of fabric, it is intended to include any suitable garment which extends about the body of the child and may be secured at the central or lower portion thereof to the sheet. It is also intended to include a harness of any construction by which the child may be safely and securely fixed in position with respect to the sheet.

In operation, the cover 10 may be secured to the bed with the tie members at the corners of the cover being secured to the sides of the bed. In this manner a lateral tension is exerted upon the end portions of the cover and the end edges are maintained straight as seen in Fig. 1. The cover may be placed on the bed and there secured while the child is being placed in the bed and taken from the bed.

When the child is to be placed in the bed, the "hookless" slide fastener 21 is opened to separate the sides of the section 14 of the cover and to provide an opening extending downwardly along the central longitudinal portion of the cover. The flap 20 is turned upwardly and the sides of the section 14 are separated so as to permit the child to be placed in the opening formed by the separation of these sides.

The "hookless" slide fastener 30 of the garment 25 is opened and the child is placed within the garment with the legs of the child extending from the openings 23 and the arms extending from the openings 29. The "hookless" slide fastener 30 is then closed to secure the child within the garment 25. When the child is secured within the garment 25, the "hookless" slide fas-

tener 21 may be closed to bring together the separated sides of the section 14 of the cover.

The child is thus secured within the garment and the garment being fastened to the cover 10 holds the child in fixed position with respect to the cover 10. The attachment of the cover member 10 to the bed prevents movement of the cover 10 with respect to the bed. The flap 20 may be turned downwardly over any additional covers which are placed above the sheet or cover 10 on the bed.

The cover construction, by providing a fullness in the longitudinal portions of the cover adjacent the central longitudinal portion thereof and on either side of this central longitudinal portion, forms elongated recesses in the cover which are adapted to provide the infolds 39. These recesses on either side of the central longitudinal portion of the cover permit the child to have a freedom of movement beneath the cover particularly as to its arms and legs. In fact, by reason of the recesses and infolds formed therein, it is possible for the child to turn and to move its legs and arms within the cover without disturbing either the position of the cover with respect to the bed or the position of the garment with respect to the cover. The infolds 39 are preferably sufficiently large to allow the child's leg, for example, to be placed across the central longitudinal portion of the cover so that both of the child's legs may be disposed on the same side of the central longitudinal portion of the cover.

When the child is to be removed from the bed, it is necessary only to release the slide fasteners 21 and 30 and withdraw the child from the garment 25 through the opening formed by the sides of the section 14 of the cover.

The attachment of the lower portion of the garment to the central portion of the cover 10 avoids any danger of the child becoming entangled in the fastening means and avoids the danger of strangulation which is present with harness construction wherein the harness is fixed by means of an attachment at the upper portion of the body.

In the modified form of garment shown in Figs. 9 to 13, the child is placed in the garment and withdrawn therefrom in the same manner as in the principal embodiment. In this modified form of garment, the child's arms and hands are completely enclosed within the sleeves 47 and are thus protected from exposure.

Although the invention has been illustrated with reference to particular embodiments and has been described in connection with specific elements of construction, it is obvious that modifications and changes may be readily made without departing from the scope and spirit of the invention.

I claim:

1. A bed cover and the like comprising a sheet of fabric equipped with means along the central longitudinal portion thereof for releasably securing the sides of the same together, the longitudinal portions of the sheet adjacent said central longitudinal portion on either side thereof being of greater length than the central longitudinal portion and providing zones of fullness in the sheet on either side of the central longitudinal portion thereof, said zones being adapted to provide infolds in the sheet adjacent said central longitudinal portion thereof, means for securing the edges of the sheet to a bed, and a fastening member attached to said portion of the sheet adjacent said first-mentioned means and acces-

sible to the opening formed by the separation of said sides, said fastening member being adapted to be removably fixed about the body of a child.

2. A bed cover and the like comprising a sheet of fabric equipped with a slide fastener along the central longitudinal portion thereof for releasably securing the sides of the same together, the longitudinal portions of the sheet adjacent said central longitudinal portion on either side thereof being of greater length than the central longitudinal portion and providing zones of fullness in the sheet on either side of the central longitudinal portion thereof, said zones being adapted to provide infolds in the sheet adjacent said central longitudinal portion thereof, means for releasably securing the edges of the sheet to a bed, and a garment attached to said portion of the sheet adjacent said fastener and accessible through the opening formed by the separation of said sides, said garment being adapted to be removably secured to the body of a child and being equipped with portions for receiving the body, legs and shoulders of a child.

3. A bed cover and the like comprising a substantially rectangular sheet of fabric, a slide fastener extending from the edge of the sheet to the central portion thereof along the central longitudinal portion of the sheet, said fastener being arranged to releasably secure the sides of the sheet together, the longitudinal portions of the sheet adjacent said central longitudinal portion on either side thereof being of greater length than the central longitudinal portion and providing a fullness in the sheet on either side of the central longitudinal portion whereby elongated recesses adapted to provide infolds are formed in the sheet adjacent said central longitudinal portion, reinforcing means in the central portion of said sheet adjacent the inner end of said fastener, tie members at the corners of said sheet for releasably securing the same to the sides of a bed whereby the sheet is fixed in position and the end edges are maintained straight, and a garment secured at the lower portion thereof to said reinforcing means and accessible through the opening formed by the separation of the sides of the sheet when said fastener is released, said garment being equipped with portions for receiving the body, legs and shoulders of a child.

4. A bed cover and the like comprising a sheet of fabric, said sheet being equipped with longitudinal portions adjacent the central longitudinal portions of the sheet and on either side thereof of greater length than the central longitudinal portions and providing zones of fullness in the sheet on either side of the central longitudinal portion thereof, said zones being adapted to provide infolds in the sheet adjacent said central longitudinal portion thereof, means for releasably securing the edges of the sheet to a bed, and a garment attached to the central portion of the sheet and adapted to be removably secured to a child, said garment being provided with a body portion, with portions extending about the shoulders and legs of the child and with sleeves for receiving and completely enveloping the arms of the child, only the portions of the garment which are received about the lower portion of the body and the legs of the child being attached to the sheet.
5. A bed cover and the like comprising a sheet of fabric, means for releasably securing the periphery of the sheet to a bed, a fastening member for releasably receiving the body of a child and providing a crotch portion between the legs of the child, and means for securing said sheet to the crotch portion only of the fastening member.
6. A bed cover and the like comprising a sheet of fabric, means for releasably securing the edges of the sheet to a bed, a garment for releasably receiving the body and legs of a child and providing a crotch portion between the legs of the child, and means for securing the central longitudinal portion of the sheet to the crotch portion only of said garment.
7. A bed cover and the like comprising a sheet of fabric, said sheet being equipped with zones of fullness adjacent the central longitudinal portion thereof adapted to form infolds in the sheet, a garment adapted to be releasably secured to a child, said garment being provided with a body portion, with portions extending about the shoulders and legs of the child and with a crotch portion between the legs of the child, and means for securing the central longitudinal portion of the sheet to the crotch portion of the garment.
